(57) **CLAIM**

The ornamental design for a textile product with marigold pattern, as shown and described.

DESCRIPTION

The sole FIGURE is a plan view of a textile product with marigold pattern, showing one repeat unit of my new ornamental design. The unit repeats uniformly throughout the length and width of the textile product. A specific length and width of the sheet material forms no part of the claimed design. The broken lines in the drawing represent the boundaries of the repeat unit.
